UNITED STATES PATENT OFFICE

156,067

DESIGN FOR A ROLL MOLDING MACHINE

John A. Boston, Belleville, N. J., assignor to Thomson Machine Company, Belleville, N. J., a corporation of New Jersey

Application August 14, 1948, Serial No. 148,123

Term of patent 14 years

(Cl. D55—1)

To all whom it may concern:

Be it known that I, John A. Boston, a citizen of the United States of America, and a resident of Belleville, in the county of Essex and State of New Jersey, have invented a new, original, and ornamental Design for a Roll Molding Machine, of which the following is a specification, reference being had to the accompanying drawing, forming a part thereof.

Figure 1 is a perspective view of a roll molding machine, showing my new design, viewing it from the rear and one side thereof;

Figure 2 is a perspective view of the machine, viewing it from the front and the other side thereof, and

Figure 3 is a top plan view of the machine.

I claim:

The ornamental design for a roll molding machine, as shown.

JOHN A. BOSTON.
